BLADE ATTACHMENT

George J. Huebner, Jr., Detroit, and David M. Borden, Huntington Woods, Mich., assignors to Chrysler Corporation, Highland Park, Mich., a corporation of Delaware

Application September 1, 1948, Serial No. 47,174

3 Claims. (Cl. 253—39)

1

The present invention relates to blading, and more particularly to blading of the side entry type for use in elastic fluid utilizing apparatus and has for an object the provision of an improved fastening means for blading of this character.

Another object of the invention is to provide novel securing means for retaining a side entry blade in its mating rotor groove, which securing means can be released and the blade removed without necessarily affecting the securing means for all other blades in its row.

Still another object of the invention is to provide novel securing means for side entry blades of elastic fluid utilizing apparatus, which securing means can be released to permit removal of and re-insertion of any desired blade without disturbing the setting of adjacent blades.

A further object is to provide a blade attachment such that its carrier may bear the configuration of a large hollow cylinder or frustum and have thus imparted to it an inherent lightness along with a natural structural rigidity.

Still a further object is to produce a blade structure wherein the carrier lends itself to a single integral casting construction which is simple and relatively cheap to produce.

Yet a further object is to produce blade structure susceptible of ready and easy insertion and removal.

Yet another object is to avoid the undue weakening of the spindle through the formation therein of the spaces intended for the accommodation of the blades.

While blade-fastening means of the character hereinafter disclosed will be found useful in many situations and types of apparatus, it is particularly useful in compressor and turbine apparatus for gas turbine power plants.

These and other objects are effected by the invention as will be apparent from the following description and claims taken in connection with the accompanying drawings forming a part of this application in which:

Fig. 1 is a longitudinal view of apparatus embodying the present invention, portions of the apparatus being broken away for the sake of clearness;

Fig. 2 is a fragmentary plan view of a compressor drum showing a row of impeller blades partially broken out and flanked by the strips relieved to accommodate the companion guide vanes;

Fig. 3 is a fragmentary transverse section through the compressor drum shown in Fig. 2;

Fig. 4 is a fragmentary perspective view of the

2

compressor drum shown in Figs. 2 and 3 and brings out details of the securing and locking arrangement provided for the blades;

Fig. 5 is a view similar to Fig. 3, but shows how the invention may be applied to a tapered drum; and

Fig. 6 is a perspective view of a moving blade as appears in the assembly showing of Fig. 5.

The phraseology or terminology employed herein is for the purpose of description and not of limitation and it is not intended to limit the invention claimed beyond the requirements of the prior art.

In the drawings there are illustrated by way of example, certain embodiments of the present invention as applied to the apparatus as will be described in connection with Figure 1. It may be used on a straight drum spindle, on a tapered drum spindle, or on a combination drum spindle. It will be understood that the invention may be applied to turbine blading as well as to compressor or other blading. As to the particulars of Fig. 1, the power plant shown may comprise in general the outer casing structure 10 open from end to end and having a central core structure 11 which may provide an annular flow passage 12 extending fore and aft with respect to the aircraft in which it is mounted. The central core structure 11 may be supported by the casing structure 10 along its longitudinal axis and may include a hollow fairing cone 14 defining with the forward or left end of the casing 10, as viewed in Fig. 1, the inlet portion of the flow passage 12.

The core structure also includes on the spindle, 35 the rotor 17 of an axial flow compressor 18, the fixed blades of which may be carried by the casing 10, the rotor 19 of a turbine 21, and a conical tailpiece 22 which may define with the rear end of the casing structure, a propulsion 40 nozzle 23. The intermediate portion of the core structure between the compressor and the turbine may comprise an inner wall structure 24 which may house a shaft 25 connecting the turbine rotor 19 and compressor rotor 17 and defines with the casing 10 an annular combustion chamber 26. The shaft 25 may be journaled in suitable bearings 25a carried by the outer casing.

The power plant may operate substantially as follows: Air may enter the casing 10 at the inlet of the flow passage 12, may be compressed by the compressor, and may flow into a diffuser or convergent portion 35 of the flow passage which effects a further compression of the air. The hot gases or motive fluid comprising the products of combustion and the excess air heated by the com-

bustion, on leaving the combustion chamber 26 may be directed by fixed guide vanes or nozzles 38 of the turbine 21 into the blade passage of the turbine rotor 19. The spent gases leaving the turbine may be discharged through the propulsion nozzle 23 at a high velocity so that the remaining energy in the motive fluid is available to propel the aircraft.

The present invention is particularly concerned with the novel means employed for preventing axial displacement of the compressor and/or turbine blades with respect to their mounting grooves in their rotor drum.

With reference to Figs. 2 to 4 inclusive, there is shown a rotor drum such as may be employed in the straight portions of the spindle just described. The blade portion of the blading proper, as shown, is purely fanciful and happens to be in the form of an impeller vane assembly. The invention may also be applied to a turbine bucket which may be carried, for instance, on the straight turbine drum of Figure 1.

The blade portions 40, 42, and 44, as shown, are adapted to fit on a cylindrical strip or segment 48 incorporated on the face of the compressor drum. This strip 48 may be flanked by two congruent strips or segments 46 and 50 which may be faced off plain. The blade-holding strip may be provided, however, at its periphery with radiating teeth 52, 54, and 56, which may carry at their tip or crest, transverse lugs shown at 58. Successive teeth such as 54 and 56 thereby may define transverse T-slots having an enlarged groove portion 60 and a narrow neck-like portion 62. These slots penetrate from the plane represented by the crest of the teeth down to a depth which may be on a lower level with the plain strips such as at 46. This groove or slot is frequently referred to in the elastic fluid industries as being of the "keyhole" type.

As may be observed particularly in Fig. 2, these grooves while extending generally in an axial direction may be inclined somewhat to the longitudinal axis of the spindle. They may be cut so as to have straight side entry even though they do not afford straight side entry even though they are open to side entry of a description. The blade proper 42 may be observed to comprise a vane assembly or blade portion 64 and a root throat portion 66. The throat portion 66 may terminate in an enlarged end flange 68 giving it in effect a T appearance, adapted to be received by the groove 60.

As to its manufacture, each blade may, for example, be milled from a solid piece of steel, bronze, Monel, stellite or other metal. The cross sectional form of the blades and the manner in which they are tanged into slots in the rotor drum are not necessarily new. Since their slots are inclined at an acute angle to the length of the strip, the blades are adapted for insertion in side entry at an oblique angle. The blade may be placed in the recess or relieved area represented by strip 46 and then forced at an angle to the spindle axis into the counterpart slot. The lugs 58 provide a centripetal shoulder arrangement whereby the roots and blades are secured against centrifugal forces acting on them during operation.

To prevent axial shift of the blades once installed, filler rings such as at 70 and 72 may be provided. These rings may consist of flat strips equal in thickness approximately to the working depth of the blade slots just described. The filler rings may be adapted to fit in the bottom

5 of the recess formed by 46 and may comprise a series of arcuate segments. As appears in Fig. 2, the segments may abut one another and depending on their length expose a suitable number of blades to insertion or removal upon being detached.

10 The particular segments shown in Fig. 3 have been provided with an aperture 78 adapted to register with a tapped bore 80 provided in strip 50. The segment may be fastened to the cylindrical strip 50 by a detachable screw means, such as shown at 82, or some other common expedient. In order to remove one of the blades the filler segment of the ring on either side as involved, 15 may be removed and the blade quickly slipped out into the open over strip 50. Then a new blade may be inserted and the segment re-installed. These filler rings serve not only to lock the blades in place but provide a smooth surface to define and direct the flow of the fluid passing through the turbine. This attachment, perfectly suitable for use on a turbine rotor, may be used too throughout an entire compressor rotor, the idea also being that the outer casing walls 20 will be tapered inwardly to accommodate the region of the shorter blades as in the diffuser area.

25 For another application of the invention, shown in Figs. 5 and 6 is a tapered type drum. This particular adaptation may be employed as well in a combination straight-tapered drum for a compressor or in a turbine rotor where different stages of blading are used. In any case, the outer housing 84 may have an axially straight 30 configuration while the drum may have a flare imparted to it in order to accommodate the diminishing sized blades. The blade represented at 86 happens to incorporate the impeller type. It comprises a vane assembly or 35 blade portion 88 which may be adapted to fit in a holding strip or segment 92 formed in the face of the rotor drum. Segment 92 may be flanged on either side by a segment or strip 90 and 94 which provide an outwardly facing plain cylindrical surface. Strip 94 may be seen to have a stepped relation as to strips 92 and 96, with strip 40 94 lying at the unrelieved end of the slot and strip 92 and on level with the tip.

45 The actual slot and root arrangement is similar in detail to structure previously described. Along the base circle of the blade holding slot is aligned the surface of strip 90. Provided for each one of these sections such as 90 and 92 may be a transverse flange or rib 96 to provide for centrifugal and other forces exerted on the drum during operation. On the step 94 may be seen a 50 wedge-shaped filler ring 98. Since access to the step 94 is substantially unobstructed, this ring 98 is preferably of unitary form and may be inserted as one piece over the teeth of strip 92 and onto the step.

55 The wedge-shaped fillers 98 and 102 are arranged to present a frusto conical surface such as will converge with casing 84. The surface may be of regular selected pitch and is preferably smooth. Pitched in with this configuration there may be provided a baffle 104 mounted on the blade assembly 88. The wedges and baffle 60 may cooperate to present a regular inclined surface and direct the gas into a path of decreasing or increasing girth as the case may be. The baffle 104 may have its edges 105 trimmed on a bias the same as is the root portion of the blade whereby it may be inserted into position at the 65 same angle as is the blade. This inclination of

course is related to and dependent upon the angle of incidence at which the blade portions are designed to be set. The edge 105 of the baffle is adapted to abut the baffle of the blade next succeeding and present an uninterrupted ring around the rotor drum. Only a small change in the configuration of the actual blade portion may be all that is necessary to convert this same structure into an ordinary turbine bucket. The baffle in that instance will provide means for expanding the gases in going from one blade stage to the next.

It will be observed that such an attachment as is used on the tapered rotor is not susceptible of blade insertion from either side as was the straight rotor, although side entry may be used. In assemblage the annular ring on the higher step succeeding will preferably be positioned and then the blade inserted from the plain portion of the lower level next preceding. The blade will then abut against filler rings on either side and/or the higher strip such as at 94 on the higher side depending of course on whether the slot has been extended by undercutting a small distance beneath the filler 98. The blades may thus be firmly locked in place with no opportunity for axial slip or dislodgement.

In practice the present invention may be found to be highly desirable for use in attaching blades to spindles comprising turbine and blower rotors, and the like, operating at high speeds since it makes possible the mounting of the blades therein without localized weakening of the spindle. The spindle is provided with individual slots for the blades which may therefore be placed in assembled position or removed when required without disturbing adjacent blades. Moreover, each blade being inserted in an individual slot, the peripheral portion of the spindle may remain uniformly strong. No part of the slot serving to accommodate a blade is subjected to the wear occasioned by the repeated insertion of blades into and the moving thereof through a single slot as is the case in many structures of this type. The blades will therefore retain their initial fits within the slots indefinitely.

What is claimed is:

1. In a gas turbine power plant incorporating elastic fluid utilizing apparatus having an annular flow passage defined by the combination of a cylindrical outer casing, a hollow rotor having a tapered segment in the outer face, the rotor comprising a succession of stepped cylindrical strips on said tapered segment alternating with conjoined strips integral therewith having straight grooves at the periphery disposed at acute angles to the length of the respective strip, said grooves extending across said strip from one end to the other end thereof, and a number of moving blades having roots inserted in said grooves, with generally sloping deflecting baffles secured to said blades and adapted to divide said blades into at least two sections located radially outward of each other, the baffles defining a generally predetermined pitch cone, and a number of moving wedge fillers bearing circumferentially on the stepped cylindrical strips, the fillers of successive stepped strips presenting their wedge faces in general conformity with said pitch cone and pitching with the appertaining baffles of the included blades to form said tapered segment.

2. For use in elastic fluid utilizing apparatus of the axial flow type, the combination with a hollow rotor having thereabout a succession of

integral coaxial annular strips of limited width and each bearing through slots extending diagonally from one lateral side of the strip to the other side and undercutting centripetal shoulders thereon, the successive strips being separated by a plain spacing segment of the same limited width but recessed radially below the succeeding strip, of a plurality of blades having enlarged roots received in said slots with the enlarged roots engaging the centripetal shoulders, the root of each blade when assembled being substantially coextensive with the strip to which it is mounted and as incident to being assembled being receivable on the immediately preceding adjacent segment whereby for assemblage it may occupy the recess afforded by said adjacent segment preparatory to entry into the root-receiving slot thereof, and a unitary ring constituting filler means detachably occupying the recess offered by each segment, the width of the filler means being substantially the same as said limited width in common to the strips and segments, said unitary ring constituting said filler means being adapted to flank the blades abutting them generally on each side.

3. For use in elastic fluid utilizing apparatus of the axial flow type, the combination with a hollow rotor having thereabout a succession of integral coaxial annular strips of limited width and each bearing through slots extending diagonally from one side of the strip to the other and undercutting centripetal shoulders, the successive strips being separated by a plain spacing segment of the same limited width but recessed radially below the succeeding strip, of a plurality of blades having enlarged roots received in said slots with the enlarged roots engaging the centripetal shoulders, the root of each blade being when assembled, substantially coextensive with the width of its root-receiving strip and as incident to assembly being receivable on the immediately preceding adjacent segment whereby for assemblage it may occupy the recess afforded by said adjacent segment preparatory to entry into the root-receiving slot therefor, and filler means detachably occupying the recess afforded by each segment, the width of the filler means being substantially the same as said limited width in common to the strips and segments, said filler means being adapted to flank the blades abutting them generally on each side and comprising a unitary flat ring of substantially the same depth of thickness as its recess and adapted to slide over the strip preceding for installation onto and removal from its segment.
